UNITED STATES PATENT OFFICE.

CHARLES A. REED, OF WILLIAMSPORT, PENNSYLVANIA.

APPARATUS FOR MAKING ORNAMENTAL ROPE.

1,392,795.

Specification of Letters Patent. Patented Oct. 4, 1921.

Application filed March 15, 1920. Serial No. 365,873.

To all whom it may concern:

Be it known that I, CHARLES AUGUSTUS REED, a citizen of the United States, and a resident of Williamsport, in the county of 5 Lycoming and State of Pennsylvania, have invented certain new and useful Improvements in Apparatus for Making Ornamental Rope, of which the following is a specification.

10 My invention relates to sewing machines generally and particularly to an attachment therefor. The purpose of such attachment when used in conjunction with a sewing machine is to provide an apparatus for making 15 ornamental rope embodied in my Letters Patent #1,346,462, patented July 13, 1920. It is also a purpose of my invention to provide an apparatus of the above described character which simultaneously stitches and 20 cuts the strips of paper comprised in the ornamental rope so that when the strips are subjected to a twisting operation by a device separate and independent from the present invention, the ornamental rope embodied in 25 my co-pending application is produced.

I will describe one form of apparatus embodying my invention, and will then point out the novel features thereof in claims.

30 In the accompanying drawings:

Figure 1 is a view showing in side elevation one form of apparatus embodying my invention.

Fig. 2 is a horizontal sectional view taken 35 on the line 2—2 of Fig. 1 and looking in the direction of the arrows.

Fig. 3 is a vertical sectional view taken on the line 3—3 of Fig. 2 and looking in the direction of the arrows.

40 Fig. 4 is an enlarged plan view of the slide plate shown in Fig. 2 and the parts carried thereby.

Figs. 5 and 6 are detail perspective views of parts of the apparatus shown in the 45 preceding views.

Similar reference characters refer to similar parts in each of the several views.

Referring specifically to the drawings and particularly to Figs. 1, 2 and 3, I have 50 here shown a portion of a conventional form of sewing machine including a table T having a suitable opening through which extends a feed bar B which is movable laterally to coact with a presser foot F for effecting the feeding of the material to be 55 stitched transversely of a needle N. The

presser foot F and the needle N are secured to the lower ends of vertically disposed shafts S and S', respectively, which are mounted for reciprocating movement with 60 in a head H.

The attachment embodying the subject matter of my invention comprises a slide plate of a form shown in Fig. 2 which has a dove-tail connection with a suitable recess 65 formed in the upper side of the table T at a point directly below the head H. This plate is designated at P and as shown in Fig. 4, it is provided with an opening 15 in which the feed bar B works, and a relatively large opening 16 in which works a horizontal cutting blade C. The blade C has a cutting edge c and is mounted for movement across the opening 16 by a pair of guide members designated generally at 70 75 G and G', respectively. The guide members G and G' are of identical construction, each comprising an upper plate 17 and a lower plate 18 secured to each other by means of a screw 19 and to the plate P by 80 means of screws 20. The plates 17 and 18 are associated to provide channels in which the blade C is slidably fitted so that the latter is free to move within the guide members and transversely of the opening 16, as 85 clearly shown in Fig. 3. As shown in Figs. 3 and 4, the blade C is urged in the direction of the feed bar B by a leaf spring 21 which is provided with a head 21^a that bears against one edge of the blade. The 90 spring 21 is supported in a socket 22^a formed on one end of a plate 22, as clearly shown in Fig. 6, such plate being secured to the under side of the slide plate P as shown in dotted lines in Figs. 2 and 4. By 95 means of screws 23 which work in slots 22^b formed in the plate, the plate as a unit is adjustable longitudinally to properly adjust the spring 21 with respect to the blade C.

As illustrated to advantage in Fig. 4, the 100 cutting edge c of the blade C in its normal position is spaced from the adjacent forward edge of the opening 16 so as to provide a slot 16^a, and arranged adjacent the opposite ends of this slot are lips 18^a formed 105 on the confronting edges of the plates 18.

Coacting with the horizontal blade C are a pair of blades C' and C^a which are secured for vertical reciprocating movement by means of a clamp K secured to the lower 110 end of the shaft S'. As shown in Fig. 5, the clamp K comprises a sleeve 24 secured to

the shaft S' by a set screw 25 and provided with an extension 26 having laterally disposed wings 27 and 27^a on which the blades C' and C², respectively, are supported. As 5 illustrated to advantage in Fig. 2, the wings 27 and 27^a are obliquely disposed so that the blades C' and C² assume corresponding positions, for a purpose which will be hereinafter described. As shown in Fig. 5, the 10 blades C' and C² are adjusted vertically upon the wings 27 and 27^a by means of screws 28 and 28^a which work in slots 29 and 29^a formed in the blades C' and C², respectively. As shown in the same figure, the lower edges 15 30 and 30^a respectively of the blades C' and C² are inclined downwardly from the inner vertical edges and are beveled to provide cutting edges which are adapted to coact with the cutting edge c of the blade C. The purpose of this arrangement of the cutting edges 20 of the blades C' and C² is to secure a shearing action when they contact with the cutting edge of the blade C so that a proper cutting is effected of the strips of paper of 25 which the ornamental rope is comprised.

For feeding the strips of paper to the apparatus, I provide a pair of arms A and A' which are tapered toward their free ends as 30 shown in Fig. 2, and are constructed to provide coacting guide channels. As shown in Fig. 2, the arms A and A' are provided with extensions 31 and 31^a respectively, at points intermediate their ends, such extensions being secured to the table T by means of screws 35 32. The forward or smaller ends of the arms A and A' when in proper position are disposed between the guide members G and G' so that when the strips of paper are introduced to the rear or larger ends of the 40 arms they can be moved forwardly through the arms and into proper position with relation to the blades C, C' and C².

In operation, the strips of paper of which the ornamental rope is to be formed are fed 45 into the arms A and A' in the manner previously described until their free ends are disposed between the presser foot F and the feed bar B. The apparatus is now ready for operation so that when a vertical reciprocation of the presser foot F and the needle N is effected, the former coacts with the feed bar to effect a feeding of the strips transversely of the needle, it being understood 50 that through the medium of the feed bar B such a feeding is rendered intermittent. When the needle N descends during the operation of the apparatus, the several strips of paper comprised in the ornamental rope are pierced and stitched by the thread carried 55 by the needle in the usual manner, this stitching taking place along the longitudinal axis of the strips. Subsequent to this stitching operation, the blades C' and C² being fixed to the shaft S' also descend into the 60 slot 16^a and engage the cutting edge c of the 65

horizontal blade C thus effecting a transverse cutting of the paper strips, at opposite points with respect to the stitching. By virtue of the arrangement of the blades C' and C², a rearward movement of the blade C 70 is effected when it is engaged by the blades C' and C², the lower extremities of the cutting edges 30 and 30^a coming into contact with the straight edge c effects a shearing 75 of the paper strips so that a clean and rapid cutting of the paper is secured. It will be understood that after each cutting operation, the blade C is returned to its normal position under the action of the spring 21 so that each succeeding operation effects a similar movement of the blade to secure the shearing action just mentioned. When the blades C' and C² descend into contact with the blade C, they are accurately guided into proper position with respect to the latter by 80 the lips 18^a, such lips also serving to retain the needle shaft S' in correct position so that an accurate stitching of the strips can be effected.

By the continuance of the above operation, 90 the several strips of paper are stitched together and cut at frequent intervals upon opposite sides of the stitching to form minute strands of paper so that when the rope is subjected to a twisting operation by an 95 apparatus (not shown) an ornamental rope having radially extending fringe is produced.

From the foregoing operation taken in conjunction with the accompanying drawings, 100 it will be manifest that I have provided an attachment for sewing machines which in conjunction with the latter provides an apparatus capable of stitching a plurality of strips of paper together and simultaneously 105 cutting the same at two separate and distinct points, and that such cutting operation is effected by the blades which coact to produce a shearing cut thereby permitting the rapid and clean cutting of the strips. 110

Although I have herein shown and described only one form of apparatus embodying my invention, it is to be understood that various changes and modifications may be made herein without departing from the 115 spirit of the invention or the spirit and scope of the appended claims.

What I claim is:

1. An apparatus of the character described comprising, feeding means, stitching means, and cutting means including a pair of blades movable by said stitching means and disposed upon opposite sides of the line of stitching and substantially transversely thereto, and a third blade movable by the first two blades to effect a shearing cut. 120

2. An apparatus of the character described comprising, means for feeding a plurality of strips of material, means for 125

stitching the strips along their longitudinal axes, and means at opposite sides of the line of stitching and substantially transversely thereto for cutting the strips at intervals 5 and upon opposite sides of the longitudinal axes thereof.

3. An apparatus of the character described comprising, a table, a plate movably supported within the table and urged 10 to a predetermined position, a needle mounted for reciprocating movement above the table, obliquely disposed blades movable with the needle and adapted to engage the first blade to move the latter against its 15 urge for the purpose described, and means for feeding a plurality of strips of material across said table and beneath said needle and blades.

4. An attachment of the character described comprising, a slide plate, guide members supported on the slide plate, a blade movable in said guide members, means for urging said blade to a predetermined position, a clamp, and a pair of 25 blades carried by said clamp and adapted to coact with the first blade in the manner described.

5. An attachment of the character described comprising, a slide plate, guide members carried by the slide plate, a blade 30 slidable in said guideways, a spring engageable with said blade for urging the same to a predetermined position, a clamp, and a pair of blades supported in oblique 35 relation upon said clamp and adapted to coact with the first blade for the purpose described.

6. An attachment of the character described comprising, guide members, a blade 40 slidable in said guide members, a spring for urging the blade to a predetermined position, means for adjusting said spring to vary the urged position of said blade, and a pair of obliquely disposed blades having 45 inclined cutting edges and movable at right angles to the first blade.

7. An attachment of the character described comprising, guide members, a blade slidable in said guide members, a spring for urging the blade to a predetermined position, means for adjusting said spring to 50 vary the urged position of the said blade, a pair of obliquely disposed blades having inclined cutting edges, and a pair of lips formed on said guide members for the purpose 55 described.

8. An apparatus of the character described comprising, a table, a plate slidable in the table, a feed bar movable in the table and plate, a reciprocating presser foot, a reciprocating needle, guide members carried by the plate, a blade slidable in said 60 guide members, means for urging the blade to a predetermined position, a pair of blades movable with said needle, and at right angles to the first blade, said pair of blades being obliquely disposed with relation to each other and having inclined cutting 65 edges, and feeding arms supported on said table and extending between said guide 70 members.

9. A cutting apparatus comprising, a plate mounted for sliding movement, means for urging said plate to a predetermined position, and a pair of reciprocating blades 75 movable at right angles to the first plate, said pair of blades being obliquely disposed with respect to each other and adapted to engage the cutting edge of the first blade in a manner to move the latter against said 80 urging means to effect a shearing action between the blades.

10. A cutting apparatus comprising, a plate mounted for sliding movement, means for urging the blade to a predetermined 85 position, a pair of cutting blades movable at right angles to the first blade and adapted to engage the cutting edge of the latter in a manner to move the plate against said 90 urging means, said pair of blades being adjustable and having inclined cutting edges.

CHARLES A. REED.
